UNITED STATES PATENT OFFICE.

ROBERT F. BARTON, OF PAPILLION, NEBRASKA.

DESIGN FOR A GARDEN-HOE.

57,302.

Specification for Design.

Patented Mar. 15, 1921.

Application filed July 14, 1920. Serial No. 396,317. Term of patent 3½ years.

To all whom it may concern:

Be it known that I, ROBERT F. BARTON, a citizen of the United States, residing at Papillion, in the county of Sarpy and State of Nebraska have invented a new, original, and ornamental Design for a Garden-Hoe, of which the following is a specification, reference being had to the accompanying drawing, forming a part thereof.

Figure 1 is a side view of a garden hoe, showing my new design. Fig. 2 is a plan view of the same.

I claim:

The ornamental design for a garden hoe, as shown.

In testimony whereof, I have affixed my signature in presence of two witnesses.

ROBERT F. BARTON.
